CLAIM

The ornamental design for a hair trimmer, as shown and described.

DESCRIPTION

FIG. 1 is a first perspective view of a hair trimmer of the present invention;

FIG. 2 is a second perspective view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a front elevational view thereof; and,

FIG. 8 is rear elevational view thereof.

The broken lines are shown for illustrative purposes only and form no part of the claimed design.
